MULTIPLE HANGER RACK

J. Herbert Hamilton, Auburn, Maine

Application January 24, 1946, Serial No. 643,086

5 Claims. (Cl. 211—46)

1

My present invention relates to multiple hanger racks.

Embodiments of my invention are suitable for use in factories, or other workshops, where textile fabrics, such as sheets, pillow cases, blankets, curtains, and similar articles are to be sewn, hemmed, or otherwise operated upon.

Broadly, my improved rack consists of a plurality of swinging hangers arranged substantially parallel to each other on a suitable framework, which framework in turn is mounted on an overhead track system, or if desired, the plurality of swinging hangers could be mounted on or attached to any suitable stationary or portable support.

Specifically, and in the preferred embodiment of my invention, the swinging hangers are arranged in vertical banks and swing horizontally on vertical pivots in such a manner that any of the materials thereon can be operated upon without disturbing the materials on the rack elements on either side thereof.

Because of the design and compactness of the hangers forming a unit of my invention, a large amount of material can be accommodated in a small space. The racks are made with a desired number of hanger elements per rack which allows the output per operator to be kept in units of racks, and to facilitate the computation of wages per employee.

Further, where the articles are, for example, sheets, the same are kept off the floor, thus keeping the same clean and free from excessive wrinkles. Also, by keeping the sheets suspended, they are subjected to a minimum amount of handling during the necessary sewing operation, and rehandling from one operation to another is eliminated, thereby keeping them smooth and preserving the mill finish of the cloth. Again, the use of devices of my invention increases production by expediting the passage of materials through the plant.

An object of my invention therefore, is an improved rack for handling sheet material.

Another object is an improved rack for supporting and transferring sheet material during the performing of fabricating operations thereon.

Other objects and novel features of the construction and operation of apparatus embodying my invention will appear as the description of the invention progresses.

In the accompanying drawings illustrating a preferred embodiment of a multiple hanger rack:

Figure 1 is a front elevation.

Figure 2 is a plan view, and

2

Figure 3 is a side elevation.

Referring to the drawings, 11 designates a horizontal support on which is swingingly mounted, intermediate the ends, the spaced rack supports 12. Rack supports 12 are constrained against longitudinal movement on the horizontal support 11 by collars 13 arranged on either end thereof, and held in position by safety set screws 14, lock washers 15, and jam or lock nuts 16.

Each rack support 12 is provided with a boss 17, drilled and tapped to receive the threaded end of a square headed bolt 18 which passes through a hole in the body of a two wheel trolley 19 which runs on the track of a monorail conveyer system (not shown). On the bolts 18 are lock washers 20 and lock nuts 21, by means of which the horizontal support 11 may be adjusted relative to the trolleys 19.

Secured one at each end of the horizontal support 11 by safety set screws 22, lock washer 23 and jam nuts 24 are right angle rack supports 25. Below the horizontal support 11, the right angle rack supports 25 are provided with holes 26, at right angles to the horizontal support 11 and through which are positioned the horizontal arms of the angle supports 27. The lower ends of the right angle rack supports 25 are drilled and tapped to receive set screws, by means of which the angle supports may be held in adjusted position on the right angle rack supports. The outer or left hand end of the angle supports are drilled to receive, as a frictional rotating fit, the horizontal arms of binder rods 28. These horizontal arms extend toward each other (see Fig. 1) and are secured together as a unit by the coupling member 29. The vertical arms of the binder rods 28 are curved inward and then downward, as viewed in Fig. 1, for a purpose to be hereinafter described.

Positioned on the lower portion of the vertical arms of the spaced angle supports 27 are the hanger supports 30. These hanger supports 30 are arranged in pairs, and in the present multiple hanger rack embodiment of my invention, I employ two pairs, arranged one above the other. The lower end of the vertical arm of each angle support 27 is provided with notches 31 in order to ensure the proper distance between the lowermost hanger support 30 and the lower edge of the horizontal arm of the angle support 27. The hanger supports 30 are secured to the vertical arms of the supports 27 by set screws 32, or by any other suitable means.

Each pair of hanger supports 30 comprises a right hand support and a left hand support. The

right hand support of each pair has a projection 33 at its right hand end, and the left hand support of each pair has a projection at its left hand end 34, as viewed in front elevation (see Fig. 1) and these projections are beveled on their inner edges at an angle of approximately 45°.

These hanger supports have hanger support projections 35 provided each with a vertically arranged hole to receive, as a frictional rotating fit, the downwardly extending member 36 of a hanger bar 37.

The hanger bars 37 are constructed of a suitable length of metal rod bent in the form of a U, the two sides of the U lying substantially parallel to each other, as shown in Fig. 3. The ends of the sides are bent at an angle to the sides to form the downwardly extending members 36, the angle being such that the sides of the hanger bars 37 extend forwardly and upwardly from hanger supports 30.

On each of the upper sides of the hanger bars 37 is mounted a length of tubing 38, preferably of fiber, and each such upper side is provided with an upwardly extending pin 39 adjacent the hanger support 30 to limit the rearward movement of the tubing 38.

In the embodiment of the invention shown in the drawings, the unit employs two banks or rows of hanger bars 37 of thirty each, arranged one above the other. Any other number of hanger bars 37 per each row or bank may be employed, depending on the character of the work being done.

Assuming that the material being worked upon is sheeting which is to be hemmed at each end, the sheeting is torn into length, then folded lengthwise, and draped evenly over the hanger bars 37. This operation is continued until the unit is filled, and is ready to be transported from one place to another along the overhead monorail, at which time the binder rods 28 are moved into position on each side of the unit so as to prevent the sheets from spreading or swinging open. This keeps the complete sheet rack compact while it is in transit from one location to another along said monorail.

When the sewing machine operator is ready to hem the sheets, she swings or lifts the binder rod upwardly so that it rests on the overhead track out of her way. She then swings or moves all sixty of the hangers to their extreme position on the right hand side until they are stopped by the beveled projections 34. Starting at the left hand of the unit the operator now grasps the lower end of the outside double fold of the sheet, passes the same through the sewing machine to make the seam, does the same with the inside fold, and as she finished hemming a sheet swings its hanger bar 37 to the left until it engages with the extreme left hand projection 34. She repeats this operation on each of the succeeding sheets until all are completed, after which she brings all sixty hangers to the center of the rack and then pulls down the binder rod to prevent the hangers from swinging out of place while the completed unit is moved along the overhead track system to the point where inspection of the product takes place, and the sheets or other items are to be folded preparatory to being placed in stock or packaged for shipment to consumers.

From the foregoing description taken in connection with the drawings, it will be evident that I have provided a construction which greatly facilitates keeping the sheets in the proper order while they are being processed. One outstanding

advantage of my construction is its compactness. By staggering the hangers relatively to one another as I have done, I reduce to the minimum the floor space needed to mount all sixty sheets closely together on their individual support and at the same time to so dispose the sheets that they may be separately processed without having them becoming entangled with one another or other complications.

Various minor changes in the arrangement of parts constituting the construction will suggest themselves to those skilled in the art and coming within the purview of the invention, and therefore I am not limited to the exact details as set out above other than as set out in the appended claims.

Having thus described my invention, what I claim as new and desire to secure by Letters Patent is:

1. An improved multiple hanger rack, comprising a support, means secured thereto for mounting the same on an overhead monorail system, a pair of angle supports secured to the support and having arms spaced apart from each other, a pair of hanger supports arranged parallel to each other and secured to the lower ends of the arms of the angle supports, a plurality of parallelly arranged hanger elements pivotally mounted at their inner ends on the hanger supports, and binder rods mounted on the angle supports at each side of the plurality of hanger elements.

2. An improved multiple hanger rack, comprising a support, means secured thereto for swingingly mounting the same on an overhead monorail system, a pair of angle supports arranged parallel to and spaced apart from each other and with one arm of each extending horizontally and the other arm extending vertically, means for securing said angle supports to the first said support, a pair of hanger supports arranged parallel to each other and constituting a unit and secured at their ends to the lower ends of the vertically extending arms of the pair of angle supports, a plurality of parallelly arranged hanger elements pivotally mounted at their inner ends on the hanger support, and binder rods mounted on the angle supports at each side of the plurality of hanger elements.

3. An improved multiple hanger rack, comprising a support, means rotatably mounted on the support for swingingly mounting the same on an overhead monorail system, a pair of angle supports, means secured to the ends of the support for holding the angle supports in adjusted position relative to the support and spacing the angle supports from and parallel to each other, said angle supports each having an arm positioned horizontally and an arm positioned vertically, a plurality of hanger supports arranged in a vertical bank and with a pair of hanger supports constituting a unit, said plurality of hanger supports being secured at their ends to the lower portion of the vertical arms of the angle supports, and a plurality of parallelly arranged hanger elements each pivotally mounted at its inner end on the hanger support and constituting a bank of hangers extending outwardly from the hanger supports.

4. An improved multiple hanger rack, comprising a support, means rotatably mounted on the support for swingingly mounting the same on an overhead monorail system, a pair of angle supports, means secured to the ends of the support for holding the angle supports in adjusted position relative to the support and spacing the angle

supports from and parallel to each other, said angle supports each having an arm positioned horizontally and an arm positioned vertically, a plurality of hanger supports arranged in a vertical bank and with a pair of hanger supports constituting a unit, said plurality of hanger supports being secured at their ends to the lower portion of the vertical arms of the angle supports, and a plurality of parallelly arranged hanger elements each pivotally mounted at its inner end on the hanger support and constituting a bank of hangers extending outwardly from the hanger supports and movable individually and collectively in vertical axes on the hanger support.

5. An improved multiple hanger rack, comprising a support, means rotatably mounted on the support for swingingly mounting the same on an overhead monorail system, a pair of angle supports, means secured to the ends of the support for holding the angle supports in adjusted position relative to the support and spacing the angle supports from and parallel to each other, said angle supports each having an arm positioned horizontally and an arm positioned vertically, a plurality of hanger supports arranged in a vertical bank and with a pair of hanger supports constituting

a unit, said plurality of hanger supports being secured at their ends to the lower portion of the vertical arms of the angle supports, a plurality of parallelly arranged hanger elements each pivotally mounted at its inner end on the hanger support and constituting a bank of hangers extending outwardly from the hanger supports, and binder rods mounted on the angle supports to limit the pivotal movement of the hanger elements.
